6 Claims. (Cl. 179—171)

1

The present invention relates to audio frequency amplifiers.

It is well known that, with class B and class AB audio frequency amplifiers, the current requirements of the output tubes vary over a considerable range. To enable an amplifier of this type to function at maximum efficiency, it has hitherto been necessary to operate the amplifier from a direct current source having very good regulation and/or to make use of a stabilizing tube or tubes, the current consumption of which varies inversely with respect to the current consumption of the amplifier.

It is the primary object of the present invention to provide a class B or class AB amplifier which requires a power supply having only moderately good regulation. This object may be accomplished in a preferred form of the invention by utilizing one or more of the tubes in the initial stages of the amplifier as stabilizing tubes in addition to their normal use as voltage amplifying or driving tubes.

The invention will now be described with the aid of the accompanying drawings which gives the circuit diagram of an amplifier comprising two tetrode output tubes, for example, of the 807 type driven by a driver tube, which may be any grid-controlled tube but which is preferably of the 6V6 type.

In this amplifier the plate and the screen grid of the 6V6 tube are connected together so that it operates as a triode. The tube is transformer coupled to, and drives the grids of the 807 tubes which operate in a push pull circuit in a well known manner.

The voltages for the electrodes of the tubes are preferably obtained from two power supplies, one of the order of 500 volts and the other of the order of 300 volts. These power supplies may be derived from the alternating current mains by means of rectifiers, which, by reason of the improvement resulting from the use of the invention, do not require a high degree of regulation, nor does the current supplied thereby need to be filtered to any great extent.

The high voltage windings connected to the rectifiers may be wound on the same core and may be energized by a single primary winding. A filter consisting only of condensers or of condensers and series resistors will be found to be satisfactory for smoothing purposes.

In the embodiment of the invention shown in the drawing, the negative terminal of the 500 volt supply is connected to ground while the negative terminal of the 300 volt supply is con-

nected to ground via the two resistors R₁ and R₂, which form part of the resistive network including the resistors R₁, R₂, R₃ and R₄. These resistors are each by-passed by a condenser of suitable capacity.

The voltage for the anodes of the 807 tubes is obtained from the positive terminal of the 500 volt supply while the screen electrodes of the 807 tubes and the anode of the 6V6 tube are fed from the positive terminal of the 300 volt supply. The cathodes of all the tubes are connected to ground.

The negative bias voltage for the 807 tubes comprises the voltage drop across the resistor R₁, while the negative bias voltage for the 6V6 tube is obtained from a voltage divider formed by the two resistors R₃ and R₄ connected in series between the negative terminal of the 300 volt supply and the positive terminal of the 500 volt supply. The 6V6 tube is adapted to function as a control tube as hereinafter described and the total negative bias voltage applied to this tube is the resultant of the voltage across the resistors R₁, R₂ and R₃; that produced across the resistor R₃ being opposite in direction to the voltages across the resistors R₁ and R₂.

Referring to the drawing, it is seen that there are two direct voltage circuits having resistors R₁ and R₂ in common. The first of these circuits can be traced from the positive terminal of the 300-volt power supply through the internal resistance of the 6V6 tube in parallel with the internal screen-to-cathode resistances of the

807 tubes, through R₁, through R₂, and back to the negative terminal of the 300-volt power supply. The point between resistor R₁ and the internal resistance of the tube is at ground potential. The second of these circuits can be

traced from the positive terminal of the 500-volt power supply, through R₄, through R₃, through R₂, through R₁, and back to the negative terminal of the 500-volt power supply, which is at ground potential. Hence the cur-

rents flowing through R₁ and R₂ can be seen to oppose each other and the resultant voltages developed across these resistors depends on the difference in the current flowing. In the preferred embodiment of the invention resistors R₁ and R₂ are traversed by the full load current of the 300-volt supply, and by only a current of low value derived from the 500-volt power supply. In this fashion, a negative voltage is derived across resistor R₁ and is applied to the grids of the 807 tubes as bias. Similarly, a

negative voltage is derived across resistors R_1 and R_2 and a positive voltage, which is somewhat less than the voltage derived across resistors R_1 and R_2 , is derived across resistor R_3 , the resultant voltage being negative and being applied to the grid of the 6V6 tube as bias.

When a signal is applied to the amplifier the plate current of each of the 807 tubes increases thus causing a decrease in the voltage of the 500 volt supply which will cause a decrease in that portion of the bias voltage applied to the 6V6 tube derived from the resistor R_3 . As this portion of the bias voltage is positive, the resultant negative bias voltage applied to the 6V6 tube will increase thereby causing a decrease in the plate current of this tube. This current flows from the cathode of the tube to the negative terminal of the 300 volt supply, via resistors R_1 and R_2 , and therefore the bias voltage applied to the grids of the 807 tubes is decreased. At the same time, the voltage applied to the screen electrodes of the 807 tubes will increase because this voltage is the difference between the 300 volt supply voltage and the voltage developed across the resistors R_1 and R_2 since these resistors are interposed between screen-cathode circuits of the 807 tubes and the 300-volt power supply. Hence a voltage drop in the 500 volt supply is offset by a decrease in the negative grid bias voltage and an increase in the screen grid voltage of the 807 tubes thus tending to maintain the optimum power output of the tubes.

Thus a decrease in the 500 volt supply, due to increased plate current with signal, is compensated by a decrease in the negative grid bias voltage and an increase in the screen grid voltage of the 807 tubes.

The degree of compensation can be varied if so desired by varying the value of the resistor R_3 .

In the operation of the amplifier, the flow of grid current in the grid circuits of the 807 tubes causes an increase in the voltage drop across the resistor R_1 , and an increase in the negative bias voltage applied to the 807 tubes. The increased voltage drop across the resistor R_1 also increases the negative bias voltage applied to the 6V6 tube thus reducing the plate current flowing through this tube. As the plate current of the 6V6 tube flows through the resistor R_1 the reduced plate current of the 6V6 tends to maintain the voltage drop across the resistor R_1 at its original value. The negative bias voltage applied to the 807 tubes is thus substantially unaffected by the flow of grid current.

Likewise, if the screen grid current of the 807 tubes increases, the increased current flows through the resistors R_1 and R_2 , thereby increasing the negative grid bias voltage applied to the 6V6 tube and decreasing the plate current flowing through this tube. Since the plate current of the 6V6 tube also flows through the resistors R_1 and R_2 the reduction in this current offsets the increased screen grid current, thereby maintaining a substantially constant voltage drop across the resistors R_1 and R_2 . Since the screen grid voltage for the 807 tubes comprises the difference between the 300 volt supply voltage and the voltage developed across the resistors R_1 and R_2 , it will be maintained substantially constant. Consequently, the screen grid voltage of the output tubes is substantially unaffected by variations in the screen grid current.

The decrease in the positive component of the negative grid bias voltage of the 6V6 tube when the 500 volt supply decreases, is partly offset by

the decrease in voltage across the resistors R_2 and R_1 when the plate current of the 6V6 tube decreases. The decrease in the positive component is also partially offset by the increase in the screen grid current of the 807 tubes when a signal is applied to the control grids of these tubes. The effect is degenerative but it cannot completely offset the increase in the negative bias voltage applied to the 6V6 tube following upon the decrease in the positive component of the bias voltage resulting from the decrease in the voltage of the 500 volt supply.

In a similar manner, any changes in the voltage of the 300 volt supply from which the potential for the screen grid electrodes of the 807 tubes is taken will produce a counter change in the bias voltage applied to the 807 tubes.

In practice, changes of voltage in the power supplies are mainly caused by variations in the current consumption of the tubes following upon changes in the level of the signal being amplified. The invention can substantially overcome these variations in the power supply voltages which would otherwise limit the optimum output of the tubes.

It is evident that the invention may also be applied to modulating systems in which class B modulators are utilized, thus reducing the degree of regulation required in the power supplies for the modulator, and such applications are intended to be within the scope of the invention.

Having now described our invention what we claim as new and desire to secure by Letters Patent is:

1. An audio-frequency amplifier comprising a driver stage having a first electron discharge tube, having an anode, a control grid and a cathode, an output stage coupled to said driver stage and having a second electron discharge tube having an anode, a control grid and a cathode, a first direct potential supply, a second direct potential supply, a resistance network connected across said second potential supply, means to apply the output potential of said first potential supply across the grid and cathode of said first electron discharge tube in series with a portion of said resistance network, means to apply the output potential of said second potential supply across the anode and cathode of said second electron discharge tube, means to connect said resistance network to the grid of said first electron discharge tube, and means to connect said resistance network to the grid of said second electron discharge tube thereby to apply negative bias voltages to the grids of said first and said second electron discharge tubes at values and in series at which a change in the potential of either of said potential supplies will vary the bias voltage applied to the grid of said first electron discharge tube to vary the anode current thereof and vary the grid bias of said second electron discharge tube to maintain the power output of said amplifier substantially constant.

2. An audio-frequency amplifier comprising a driver stage having a first electron discharge tube having an anode, a control grid and a cathode, an output stage coupled to said driver stage and having a second electron discharge tube having an anode, a control grid and a cathode, a first direct potential supply, a second direct potential supply, a resistance network connected across said second potential supply, means to apply the output potential of said first potential supply across the anode and cathode of said first electron discharge tube in series with a portion

of said network, means to apply the output potential of said second potential supply across the anode and cathode of said second electron discharge tube, means to connect said resistance network to the grid of said first electron discharge tube, and means to connect said resistance network to the grid of said second electron discharge tube to apply negative bias voltages to the grids of said first and said second electron discharge tubes at values and in senses at which a change in the potential of said potential supplies due to flow of grid current in said second electron discharge tube will vary the bias voltage applied to the grid of said second electron discharge tube to maintain the optimum power output of said amplifier substantially constant.

3. An audio-frequency amplifier comprising a driver stage having a first electron discharge tube having an anode, a control grid and a cathode, an output stage coupled to said driver stage and having a second electron discharge tube having an anode, a screen grid, a control grid and a cathode, a first direct potential supply, a second direct potential supply, a resistance network connected across said second potential supply, means to apply the output potential of said first potential supply across the anode and cathode of said first electron discharge tube and across the screen and cathode of said second electron discharge tube in series with a portion of said resistance network, means to apply the output potential of said second potential supply across the anode and cathode of said second electron discharge tube, means to connect said resistance network to the grid of said first electron discharge tube, and means to connect said resistance network to the grid of said second electron discharge tube to apply negative bias voltages to the grids of said first and said second electron discharge tubes at values and in senses at which a change in the output potential of either of said potential supplies will vary the bias voltage applied to the grid of said first electron discharge tube to vary the anode current thereof and vary the grid bias and the screen grid voltage of said second electron discharge tube to maintain the power output of said amplifier substantially constant.

4. An audio-frequency amplifier comprising a driver stage having a first electron discharge tube having an anode, a control grid and a cathode, an output stage coupled to said driver stage and having a second electron discharge tube having an anode, a screen grid, a control grid and a cathode, a first direct potential supply, a second direct potential supply, a resistance network connected across said second potential supply, means to apply the output potential of said first potential supply across the anode and cathode of said first electron discharge tube and across the screen and cathode of said second electron discharge tube in series with a portion of said resistance network, means to apply the output potential of said second potential supply across the anode and cathode of said second electron discharge tube, means to connect said resistance network to the grid of said first electron discharge tube, and means to connect said resistance network to the grid of said second electron discharge tube to apply negative bias voltages to the grids of said first and said second electron discharge tubes at values and in senses at which a change in the potential from said potential supplies due to changes in screen grid current of said second electron discharge tube will vary the bias voltage applied to the grid of said first electron discharge

tube to vary the anode current thereof and vary the grid bias and the screen grid voltage of said second electron discharge tube to maintain the optimum power output of said amplifier substantially constant.

5. An audio-frequency amplifier comprising a driver stage having a first electron discharge tube having an anode, a control grid and a cathode, an output stage coupled to said driver stage and having a second electron discharge tube having an anode, a screen grid, a control grid and a cathode, a first direct potential supply, a second direct potential supply, a resistor network comprising a first, a second, a third and a fourth resistor connected in series across said second potential supply said first resistor being connected to the negative terminal of said second potential supply, means to couple the positive terminal of said first potential supply to the anode of said first electron discharge tube and to the screen grid of said second electron discharge tube, means to connect the negative terminal of said first potential supply to the junction of said second and said third resistors, means to apply the output potential of said second potential supply across the anode and cathode of said second electron discharge tube, means to connect the junction of said third and said fourth resistors to the grid of said first electron discharge tube, and means to connect the junction of said first and said second resistors to the grid of said second electron discharge tube, and means connecting the cathodes of said electron discharge tubes to the negative terminal of said second potential supply, the resistors of said network having resistance values at which a change in the potential from said potential supplies will vary the bias voltage applied to the grid of said first electron discharge tube to vary the anode current thereof and vary the grid bias and the screen grid voltage of said second electron discharge tube to maintain the power output of said amplifier substantially constant.

6. An audio-frequency amplifier comprising a driver stage having a first electron discharge tube having an anode, a control grid and a cathode, a push-pull output stage having a second and a third electron discharge tube, said second and said third electron discharge tubes each having an anode, a screen grid, a control grid and a cathode, a first direct potential supply, a second direct potential supply, a resistor network comprising a first, a second, a third and a fourth resistor connected in series across said second potential supply said first resistor being connected to the negative terminal of said second potential supply, a transformer having a primary and a center-tapped secondary winding, means connecting one end of the primary winding of said transformer to the anode of said first electron discharge tube, means connecting the positive terminal of said first potential supply to the other end of the primary winding of said transformer and to the screen grids of said second and said third electron discharge tubes, means to connect the negative terminal of said first potential supply to the junction of said second and said third resistors, means to couple the junction of said third and said fourth resistors to the grid of said first electron discharge tube, and means to connect the junction of said first and said second resistors to the center tap of the secondary winding of said transformer, means to connect the ends of said secondary winding to the grids of said second and said third electron

discharge tubes, means connecting the cathodes of said electron discharge tubes to the negative terminal of said second potential supply, and means to apply the output potential of said second potential supply across the anodes and cathodes of said second and said third electron discharge tubes, said resistor network having values at which a change in the potential from said potential supplies will vary the bias voltage applied to the grid of said first electron discharge tube, to vary the anode current thereof and vary the grid bias and the screen grid voltage of said second and said third electron discharge tubes, thereby to maintain the optimum power output of said amplifier substantially constant.
